H. M. KNIGHT,
CONCRETE BLOCK CONSTRUCTION.
APPLICATION FILED APR. 6, 1914.

1,353,046.

Patented Sept. 14, 1920.
3 SHEETS—SHEET 3.

UNITED STATES PATENT OFFICE.

HERBERT M. KNIGHT, OF ROME, NEW YORK.

CONCRETE BLOCK CONSTRUCTION.

1,353,046.

Specification of Letters Patent. Patented Sept. 14, 1920.

Application filed April 6, 1914. Serial No. 829,757.

To all whom it may concern:

Be it known that I, HERBERT M. KNIGHT, of Rome, in the county of Oneida and State of New York, have invented certain new and useful Improvements in Concrete Block Construction; and I do hereby declare that the following is a full, clear, and exact description thereof, which will enable others skilled in the art to which it appertains to make and use the same, reference being had to the accompanying drawings, and to the reference-numerals marked thereon, which form part of this specification.

My present invention relates to construction work with made concrete blocks, including constructions where the blocks constitute the entire wall or other structure and also constructions where the blocks constitute irremovable forms to receive therewithin the mass concrete.

The purpose of my invention is to provide an improved form of such concrete block construction and to provide novel and improved means for tying or clamping the blocks to each other and to the whole structure.

A further purpose of my invention is to provide a new and improved pattern or shape for such blocks in combination with co-operating keys and to make said blocks and keys of such form and of such relation to each other as to provide a concrete block construction the parts of which are simple to manufacture, easily and quickly assembled and permanently and strongly bound together.

Another purpose is to so form the blocks and their co-operating keys that they may be combined together or used with mass concrete in a great variety of ways and shapes with a minimum of different shapes and sizes of units or blocks and yet where necessary be capable of being made in great variety but with remarkable adaptability for co-operating with each other.

Yet another purpose of my invention is to provide such a form of concrete block construction that the blocks may be adjusted to any point longitudinally of each other without impairing the operation or efficiency of the means used to hold the blocks together or to the mass concrete. Such adjustment makes possible or facilitates correct assembling of the blocks especially where they are used to form other than a plain or blank wall.

Another object of this invention is to provide a form of concrete block construction that has means for preliminarily holding the blocks together and permanently clamping them together and to the mass concrete filling or backing without at any time engaging or obstructing the outer face of the blocks. This feature is important where the outer face is specially or ornamentally finished or decorated since any means engaging such a surface is apt to injure it. Furthermore a constant view of the specially finished or decorated face materially aids in correctly placing and arranging the blocks so finished.

Figure 1 is a horizontal sectional view of the corner of a wall of concrete block construction embodying my invention.

Fig. 2 is a vertical sectional view on line 2—2 of Fig. 1.

Fig. 3 is a back view or elevation of an ordinary form of concrete block used in constructing concrete structures according to my invention.

Fig. 4 is an end elevation of the block shown in Fig. 3.

Fig. 5 is a vertical sectional view on line 5—5 of Fig. 3.

Fig. 6 is a horizontal section on line 6—6 of Fig. 3.

Fig. 7 is a cross sectional view on an enlarged scale through a reinforced concrete key and the co-operating recesses in two adjoining blocks.

Fig. 8 is a side view of a strip of concrete key utilized in concrete block construction according to my invention.

Fig. 9 is a top view of the key shown in Fig. 8.

Fig. 10 is a side view of a section of metal reinforcement such as used in the key shown in Figs. 8 and 9.

Fig. 11 is a cross sectional view on line 11—11 of Fig. 10.

Fig. 12 is a cross sectional view through a rectangular pillar, beam or conduit embodying my invention.

Fig. 13 is a cross sectional view through another form of rectangular pillar, beam or conduit.

Fig. 14 is a horizontal sectional view of a wall embodying my invention, the same being so constructed by the use of cross blocks at intervals between the exterior and interior series of concrete blocks as to produce a cellular or curtain wall construction or a wall that is alternately solid and hollow.

Fig. 15 is an isometrical view of a wall embodying my invention in several forms.

Fig. 16 is a vertical sectional view through a part of the exterior blocks of the wall 5 shown in Fig. 15.

Fig. 17 is a cross sectional view through a circular conduit composed of interior and exterior blocks and constructed according to my invention.

10 Fig. 18 is a side view of the tying means shown in Fig. 17.

Fig. 19 is an isometrical view on an enlarged scale of a portion of two blocks such as used for the interior series of the conduit 15 shown in Fig. 17.

Fig. 20 is a cross sectional view through a circular pillar constructed according to my invention.

20 Fig. 21 is a cross sectional view of a conduit constructed of concrete blocks and embodying my invention.

Fig. 22 is a diametrical sectional view on a line vertical as compared to Fig. 21.

25 Fig. 23 is a view of the edge or narrow side of a length of curved concrete key used in such constructions as illustrated in Figs. 21 and 22.

Fig. 24 is a cross sectional view through Fig. 23.

30 Fig. 25 is a cross sectional view of a system of conduits or ducts constructed according to my invention.

Fig. 26 is a cross sectional view of another form of conduits or sewers embodying my invention.

35 Fig. 27 is a horizontal sectional view through a wall constructed according to my invention and showing the exterior surface of the wall provided with inlaid work or 40 ornamentation.

Fig. 28 is a vertical sectional view on line 28—28 of Fig. 27.

Fig. 29 is a side elevation of the wall shown in Figs. 27 and 28.

45 Fig. 30 is a transverse sectional view illustrating the application of my invention in the production of curtain wall construction.

50 Fig. 31 is a cross sectional view on an enlarged scale of a nailing strip used in connection with the curtain wall or similar construction as shown in Fig. 30.

55 Figs. 32 and 33 are cross sectional views of a modified or composite form of key first as the halves of said key are assembled in the recesses of blocks and in Fig. 33 as the blocks and halves of the key are brought together into locking position.

Referring to the drawings in a more particular description, the manufactured or 60 made concrete blocks may be of any size, shape or relative proportion desired, according to the class and character of the work in hand, but the ordinary blocks 41 will have outer and inner faces 42 and 43 respectively, 65 and contact edges which for the sake of con-

venience of reference will be called top and bottom edges 44 and 45 respectively and end edges 46. It will be obvious that these terms may cease to be as apt when the blocks are turned about or are in other than perpendicular position or when the blocks are modified in shape to adapt them for special purposes or places, but on the whole the above terms will be applicable and not misleading. 70

The blocks 41 have in their end contact 75 edges 46 and also preferably in their top and bottom contact edges 44 and 45, recesses 48 having their sides 49 undercut or tapering from each other as the recess extends into the block. These recesses extend longitudinally of the various contact edges of the block and are so placed that when two blocks are brought together in desired way the adjacent or engaging contact edges will have their recesses 48 in alinement with each other. Rigid concrete keys 50 are provided of a shape adapted to fit said alined recesses 48 and adapted to be inserted longitudinally 80 therein and hold said blocks from being drawn apart except by longitudinal movement of one or both of said blocks or of said key relative to each other.

85 Preferably the recesses and their keys will be in cross section of the shape clearly indicated in Fig. 7, that is with the double 90 headed dovetail of the key 50 engaging the undercut oppositely disposed recesses 48 but it will be understood that this feature may be modified to various forms of rigid locking key longitudinally inserted in appropriate 95 movement of one or both of said blocks or of said key relative to each other.

100 For some classes of concrete block construction these recesses 48 may be provided only on opposite end edges 46 of the blocks 105 and for other forms of construction the recesses may be provided only upon the top and bottom edges 44 and 45; but for many forms of construction these recesses will be provided upon all said contact edges, namely 110 both ends 46, and top and bottom edges 44 and 45. This fully recessed block can then be keyed to the blocks adjacent thereto on all four edges. For convenience in making and assembling the fully recessed blocks I 115 prefer to have the recesses extend the full length of the opposite end edges 46 of the block but have the recesses extend only through a part, usually the central part of the top and bottom edges 44 and 45 respectively. 120

125 In order to give ample width of bearing on the engaging edges of the blocks and ample room and material for the recess and to secure solid walls adjacent thereto, I prefer to thicken the blocks at the engaging edges especially where they are also recessed. I accomplish this by providing on said blocks at such edges and extending back for a sufficient distance therefrom, ribs 130

projecting past the plane of the inner face 42 or outer face 43 of the block according to the use to be made of the block.

In the ordinary block 41 used for wall construction either with or without mass concrete fillings 58, this rib 51 will project inwardly or past the plane of the inner face 42. Likewise, in the semi-circular blocks 52 used to form a circular column illustrated in Fig. 20, in the segmental blocks 53 used for the outer casing of conduits, illustrated in Fig. 17 and in the modified form of rectangular blocks 55 shown in Fig. 12 the ribs will project inwardly; while in the semi-circular blocks 56 and segmental blocks 57 used to form conduits or sewers and the like or the inner casing thereof as shown respectively in Figs. 21 and 22 and Fig. 17, the ribs 51 project outwardly. In general the 20 ribs, as far as they are used simply to increase the contact surface at the engaging edges of the blocks, are projected in such a direction as will least interfere with the function of the structure.

In block wall construction using mass concrete filling 58 the ribs 51 are projected inwardly of the wall on both exterior and interior blocks not only to maintain an even surface on the outside and inside of the ultimate wall but also to enable the concrete filling 58 when it sets to clamp adjacent blocks to one another permanently by engaging inner sides 59 of the ribs 51 of adjacent blocks and also to enable said concrete filling 58 to permanently clamp the several blocks permanently to the mass concrete by the semi-fluid concrete entering and securing a locking engagement with the undercut inner sides 59 of said ribs 51 by which is included a tapering inner side as in Fig. 16 or an inner side 59 provided with channels or pockets 60. By the term "inner side 59 of the rib 51" is meant the face of the rib opposite the face thereof that forms part of 45 the contact edge of the block.

Furthermore the inwardly projecting ribs 51 with their inner sides 59 afford effective places for the attachment to said exterior and interior series of blocks, of concrete cross blocks 62 which are both tying and bracing members for said exterior and interior series of blocks at desired intervals. These cross blocks 62 have in their engaging or contact edges undercut recesses 48 as hereinbefore described to receive rigid keys 50 in conjunction with oppositely disposed and aligned similar recesses 48 in the said inner sides 59 of ribs 51. These cross blocks may be relatively narrow and spaced apart as indicated in Fig. 2, thus allowing the mass concrete to freely surround them, or they may be wide and used to form a partition crosswise of the wall such as may be used to produce a wall alternately solid and hollow as shown in Fig. 14.

It will be understood that for ordinary construction a slip or filling of thin concrete 63 will be used to entirely fill the slight space that may remain at different points between the concrete key 50 and the sides of the recesses 48 in order to obtain a more rigid permanent hold and in order to bind the concrete key 50 and the blocks engaged thereby into one homogeneous mass.

The rigid keys 50 will be formed of the proper size and proportion to fit the oppositely disposed recesses 48 and will for convenience in manufacture and handling be formed of considerable length but adapted to be easily separated into sections of desired length through being provided with encircling grooves or nicks 64 at intervals along the length of the manufactured key. In this way a key of considerable length may be manufactured at one time and handled as one piece, but divided up into two or more sections of desired length as required upon the construction in hand.

Preferably in order to obtain sufficient tensile strength between the two dovetailed shaped halves of the key 50 said concrete key will be provided with metal reinforcement 65 which reinforcement is conveniently and preferably formed in cross section to be of the usual I-beam type and will be so placed in the manufactured concrete key 50 as to have its opposite flanges 66 in opposite halves of the concrete key while its connecting web 67 will extend from one half of the key into the other through its narrowed or thinnest section.

Furthermore in order to allow this metal reinforcement to be as light as possible and to grasp the concrete as strongly as possible, apertures 68 are provided in the web 67 of the metal reinforcement 65. A convenient way of forming and using this metal reinforcement is to form the same in relatively short sections 69 as shown in Fig. 10 and several of these sections will be placed end to end in the usual long length of manufactured keys 50 but with the sections 69 spaced a short distance from each other in the key as indicated in dotted lines in Figs. 8 and 9. This construction sufficiently reinforces the keys and enables them to be separated into short sections as heretofore mentioned, it being understood that the encircling grooves or nicks 64 will be placed at those points in the length of the key where the sections 69 of the reinforcement do not come. In this way the reinforced keys may be readily separated into sections without having to cut through the metal reinforcement and without interfering with or loosening the engagement between the reinforcement and its encircling concrete.

In order to assist in holding the metal reinforcement at the proper place in the keys while the reinforced key is being made the

sections 69 of such reinforcement may be provided with projecting feet 70 which will support the section of reinforcement at the proper place in the mold.

5 In order to aid in preliminarily alining the concrete blocks they may be provided with a shallow groove 71 upon their upper or top edge 44 and with a correspondingly shaped and sized tongue 72 on the bottom edge 45. When these blocks are placed one on top of another the blocks may be easily adjusted to proper alining position by placing the downwardly projecting tongue 72 of the upper block into the recesses 71 upon the top edge 44 of the lower block.

10 In the projecting ribs 51 and usually as continuations of pockets 60 in said ribs are provided small holes or perforations 73 extending through said ribs and affording an opportunity for conveniently attaching to said blocks tying means 75 or 74 as indicated for instance in Figs. 14, 15, 17 and 18.

15 Where curved blocks are used as in Figs. 21 and 22 and are connected at their ends by keys fitting into alined recesses it will be apparent that these recesses will follow the curve of the block and will need keys of a similar curve. Such curved keys 50^a are shown in Fig. 23 and their position immediately prior to being inserted into these curving recesses is shown in Fig. 21.

20 It will be evident that my invention may be adapted to secure corbel or molding courses to the exterior surface of a wall by providing an undercut recess in the outer face of the blocks forming the exterior portion of the wall and that by means of this exteriorly facing recess 48 the molding or 25 corbel courses may be secured in the way hereinbefore described for the ordinary co-operating blocks. Similarly cornice courses may be secured to the wall as shown in Fig. 15.

30 45 If such a molding or corbel course is to be affixed to the exterior of a wall opposite the engaging edges of two blocks the said two exterior faces may together form the equivalent of the usual undercut recess by 40 means of recesses such as 48^a illustrated in Fig. 16 so that when the engaging wall blocks are in place a proper recess is formed to receive one-half of the usual double dovetailed key 50.

50 55 It will be apparent from an inspection of Figs. 27 to 29 that my invention is particularly applicable in concrete block construction where the exterior face of the structure is specially finished or provided with ornamental work or has inlaid work thereupon since it will be apparent that the structure can be assembled and completed without at any time requiring the engagement of any false work or forms against said special outside surface and without such outside sur-

face being engaged by permanent or preliminary holding or clamping means. Furthermore as this outer surface is at all times exposed to observation the blocks can be laid up with much greater precision and 70 can be accurately adjusted in order to maintain the pattern or the alinement of ornamental work.

5 In Figs. 32 and 33 is illustrated a form of key composed of two interlocking sections 75 50^a and 50^b which may be used in constructions embodying my invention in places where it is impossible or inconvenient to insert the key longitudinally in both recesses at the same time or to insert one-half of the 80 single solid key in one form of recess and then slide the other recess over the other half of the key. The sections 50^a and 50^b are each composed of a head 75 and a lug 76 projecting therefrom and out through the 85 reduced opening of the recess 48 in which the head 75 is held. The sections 50^a and 50^b are adapted to be inserted longitudinally into the recesses 48 and be held therein except against similar longitudinal movement. 90

95 The key is locked together by moving the sections thereof and their containing blocks toward each other relatively or from the position shown in Fig. 32 to the position shown in Fig. 33, during which movement catch faces 77 and 78 on the lugs 76 of section 50^a and section 50^b respectively will be brought into engagement with each other. Inclined faces 79 in heads 75 engaging the ends of lugs 76 may be so arranged as to 100 force the lugs toward each other as the two sections of the key are brought lug-side on to each other.

105 In Figs. 30 and 31 is illustrated a construction embodying a further modification of my invention. It is often desirable to construct a concrete wall or other structure and provide the same with an interior surface or layer of another material. Fig. 30 110 illustrates how an ordinary form of my concrete blocks with their usual undercut recesses 48 may be utilized in different positions not only to provide the usual concrete block wall but also to provide improved and convenient means for mounting the 115 surfacing or sheathing 80 of wood or other material upon the concrete wall by means of nailing strips 81 secured to said blocks by engagement with some of the recesses 48 upon said blocks. It will be noticed that all 120 the blocks shown in Fig. 30 except the cross blocks 62 are of one form though of slightly different proportions, in that all of the blocks have the ordinary undercut recesses 48 in their engaging sides 46 and upon the 125 inner side 59 of their offset ribs 51. Block 41 is used and connected in the usual way namely by engaging adjacent blocks 41^a by means of keys 50 inserted in oppositely disposed recesses and by engaging cross blocks 130

62 by means of the recesses on the inner sides 59 of inwardly projecting rib 51. The recesses in the inner sides 59 of ribs 51 of blocks 41^a receive and hold the tongue of 5
nailing strips 81 to the edge of which may then be nailed the interior surfacing 80. Block 41^b has its recesses on the inner side of its rib utilized to connect it to the cross bars 62 of the concrete wall but the recesses 10 in its sides 46 are used to engage the tongue of nailing strips 80 which on account of the position of block 41^b receive the interior surfacing 80 both upon the edge and the broad face of the nailing strips 81. It will be obvious 15 from this showing and description that the concrete blocks of standard form may thus be interchangeably used in various positions and their several recesses used interchangeable either to receive the keys 50 or the tongue of a nailing strip as may be required from the position of the block in the structure.

What I claim as new and desire to secure by Letters Patent is:

25 1. In a building construction, a plurality of blocks having inwardly extending ribs, registering dove-tail grooves formed in the abutting surfaces of the inwardly extending ribs, a double dove-tail key in the double 30 dove-tail groove, said ribs being also provided with other grooves positioned and adapted to interengage with a cementitious filler.

2. In a building construction, blocks hav-

ing inwardly extending ribs, dove-tail 35 grooves formed in the abutting surfaces of the ribs, double dove-tail keys inserted in the registering dove-tail grooves, said inwardly extending ribs being also provided with openings adapted to engage a binder. 40

3. In a building construction, blocks disposed in a vertical plane and provided with inwardly extending ribs upon their vertical and horizontal sides, said ribs being provided with dove-tail grooves, and other similar blocks having similarly inturned abutting ribs provided with similar registering dove-tail grooves, and double dove-tail keys inserted in the registering dove-tail grooves. 45

4. In a building construction, opposed 50 face blocks having inwardly turned ribs extending toward the opposite block, dove-tail grooves formed in the surfaces of said inwardly extending ribs, and cross blocks interposed between the opposed face blocks, 55 said cross blocks being provided with dove-tail grooves registering with the dove-tail grooves of the ribs, and double dove-tail keys inserted in the registering dove-tail grooves. 60

In witness whereof I have affixed my signature, in the presence of two witnesses, this 1st day of April, 1914.

HERBERT M. KNIGHT.
